ABSTRACT: A locking mechanism for an egg carton having an integrally hinged tray and cover. The locking mechanism includes a locking flap hingedly connected to the cover and foldable into overlapped relation with the inside of the cover's front wall and locking detents projecting inwardly from the inner surface of the folded flap. The carton is secured shut by interlockingly engaging the locking detents with the underside of a raised lip on the front wall of the carton's tray.

LOCKING MECHANISM FOR EGG CARTONS

This invention relates to packaging cartons, and more particularly to a new and improved locking mechanism for molded egg cartons.

Molded cartons with various types of integrally molded locking mechanisms have been provided in the past for the packaging of eggs. Exemplary of one widely used type of mechanism provides a pair of lugs on the outer surface of a flap hingedly connected to the front of the carton's tray and corresponding apertures in the front wall of the carton's lid through which the lugs extend to lock the lid to the tray.

Cartons utilizing this type of locking mechanism, however, have generally proven unsatisfactory to housewives and other users because they are difficult to open and close. The lug locking feature, for example, requires flexing of the carton's walls by the user during opening and closing to free the lugs from the apertures. Due to the inherent stiffness of the material, however, used in the manufacture of the cartons and the outward pressure of the packaged articles, it is difficult sometimes for the user to flex the structure sufficiently to allow clearance for easy opening and closing. Such difficulties, of course, are not only inconvenient to the user but render the carton and packaged articles prone to being damaged during repeated opening and closing of the carton.

In accordance with the present invention, a new and improved locking mechanism is provided for packaging cartons having hingedly connected bottom and cover sections that can assume a closed superimposed position with respect to each other.

The locking mechanism includes a locking flap hingedly connected to the bottom longitudinal edge of the cover section's front wall and foldable into overlapped relation with inside of the cover's front wall; at least one locking detent projecting inwardly from the inside surface of the flap when it is in folded position; and a raised locking lip on the top of the bottom section's front wall. The carton is secured shut by closing the cover over the tray to interlockingly engage the locking detent with the underside of the locking lip.

Preferably, the packaging carton is an egg carton and the carton and locking mechanism are of unitary molded constructions.

It is to be understood that both the foregoing general description and the following detailed description are exemplary and explanatory but are not restrictive of the invention.

The accompanying drawings which are incorporated in and constitute a part of the specification illustrate an embodiment of the invention and together with the description serve to explain the principles of the invention.

Of the drawings:

FIG. 1 is a perspective view of an open egg carton embodying the locking mechanism of this invention;

FIG. 2 is a plan view of the egg carton of FIG. 1;

FIG. 3 is a sectional view taken along the lines 3—3 of FIG. 2;

FIG. 4 is a fragmentary and enlarged view in vertical section of the front of the carton of FIG. 1 in a partially open position; and

FIG. 5 is a view similar to FIG. 4 but with the carton in closed position.

Reference will now be made in detail to the present preferred embodiment of the invention, an example of which is illustrated in the accompanying drawings.

The packaging carton illustrated in the drawings and contemplated for use with the locking mechanism of this invention is an egg carton having a cover section or lid 10 and a bottom section or tray 12. The cover and bottom sections' rear walls 14 and 16, respectively, are hingedly connected by an integral web 18. Bottom section 12 has a plurality of egg-accommodating cells 20 arranged in parallel rows. While the number and rows of cells may vary, the bottom section preferably consists of a dozen cells arranged in two parallel rows of six cells each.

A wide variety of materials may be used in the manufacture of the carton structure illustrated in the drawings. Molded paper pulp, pasteboard, plastic, and the like, for example may be used. A preferred material, however, is thermoplastic foam, such as, for example, foam polystyrene, or other polymers, such as polyethylene, polypropylene, polyvinylchloride, and the like. For purposes of illustration and as a preferred embodiment, the drawings show an egg carton and locking mechanism for the carton of unitary construction produced by vacuum molding or match-molding techniques from a sheet of polystyrene foam.

In accordance with the invention, interlocking means are provided on the front walls of the cover and bottom sections for releasably holding the carton closed. The relationship between the interlocking means and the top and bottom sections of the carton, as shown in the drawings, will be used for clarity in the specification and claims, but it is to be understood that the various parts of the interlocking means may be reversed with respect to the carton's sections without departing from the scope of the invention.

As embodied, the interlocking means includes a locking flap 22 hingedly connected by an integral web 24 to the bottom longitudinal edge of the front wall 26 of cover section 10 so that the flap can be folded into overlapped relationship with the inside surface 27 of front wall 26. Locking flap 22 has a plurality of locking detents 28, five (5) being shown in the drawings, that project inwardly from the inner surface 30 of flap 22 when it is in folded position. Each locking detent 28 has a substantially flat upper locking edge 32. As best shown in FIG. 4, a locking flange 34 that is coextensive with locking flap 22, extends beyond the detent's locking edge 32 and is substantially perpendicular thereto.

In accordance with the invention, a raised locking lip 38 is provided on the top of the bottom section's front wall 40 that is positionable inside of front wall 26 of cover section 10 when the carton is closed. When cover section 10 is closed over bottom section 12, and as best shown in FIG. 5, upper locking edges 32 of locking detents 28 engage the underside of locking lip 38, and locking flange 34 engages the forward edge 42 of locking lip 38 to lock the cover and bottom sections together.

In accordance with a preferred embodiment of this invention, and as best shown in FIG. 1, a plurality of spaced lugs 44 are provided along the top of the bottom section's front wall 40. Each lug 44 has a recessed portion 46 open at the front for receipt of a locking detent 28 and a flat top wall forming a plurality of spaced locking lips 38 corresponding to the number of locking detents 28 on flap 22.

As best shown in FIG. 1, an outwardly and laterally extending flange 50 extends around the bottom of the cover section's rear wall, its sidewalls, and a portion of its front wall, and a corresponding flange 52 extends around the top of the bottom section's walls, the flanges 50 and 52 being in substantial flush load-bearing engagement when the carton is closed. Along the front of the carton's tray, flange 52 is interrupted by the plurality of spaced lugs 44, the lugs preferably forming an extension of interior ribs 54 that form the article-accommodating cells 20 to strengthen the interlocking mechanism. When the carton is closed, the sections 52' of flange 52 between spaced lugs 44 are in flush engagement with the web 24 that forms the hinged connection between the cover section's front wall 26 and locking flap 22.

To secure the carton shut, cover section 10 is rotated about hinge 18 toward closing relationship with bottom section 12 and pressed downwardly until the lateral flanges 50 and 52 are in abutting engagement. As the carton is closing, and as best shown in FIG. 4, the forward edges 42 of lugs 44 engage the projecting surface of locking detents 28 causing locking flap 22 to pivot upwardly toward overlapped relation with the inside 27 of cover section's front wall 26.

When the carton is completely closed and locking detents 28 have cleared the forward edges 42 of lugs 44, the detents snap back into recesses 46 in lugs 44, bringing the detents' locking edge 32 into interlocking engagement with the underside of the lugs' locking lips 38. After closure, locking flange

34 on locking flap 22 abuts the forward edges 42 of the lugs to hold the flap in locking position.

To open the carton, locking flap 22 is pulled out of locked position by pulling upwardly on the carton's cover section 10. During forced upward movement of the carton's cover, locking flange 34 and the locking edges 32 of detents 28 act against the forward edges 42 of lugs 44, causing locking flap 22 to pivot downwardly and pull detents 28 out of the lugs' recesses 46.

The integral web 24, hingedly interconnecting locking flap 22 and the cover section's front wall 26 is preferably doubly creased at 60 and 62, as shown in FIG. 3, to provide a double hinge with a compressible midportion 64 that resiliently urges locking detents 28 into recesses 46 in lugs 44 when the carton is closed. Similarly, integral web 18 is also doubly creased at 66 and 68 with a compressible midportion 70 to resiliently urge the cover and bottom sections apart. Thus, locking detents 28 snap tightly into engagement with the underside of the lugs locking lips 38 when the carton is closed for more positive locking.

Preferably, and as best shown in FIGS. 3 and 4, the forward edges 42 of lugs 44 are recessed with respect to the forward edge of lateral flange 52 and a recess 72 is provided on the inside surface 27 of the dover section's front wall 26 for receipt of folded locking flap 22 to provide a substantially smooth outer surface to the front of the carton.

It is to be understood that the carton described in the drawings and utilizing the locking mechanism of this invention is a preferred carton design for eggs. The invention, however, is applicable to a variety of egg carton shapes and other similar cartons. An egg carton, for example, having three parallel rows of four egg-accommodating cells each could readily be used with the present locking mechanism.

The invention thus provides a new and improved locking mechanism for packaging cartons, and particularly molded egg cartons. The locking mechanism facilitates easy closing with automatic and positive locking, especially adaptable to automatic egg packaging equipment, and easy opening of the carton without fear of damage to the carton or its contents. Further, the locking mechanism of this invention can be integrally molded with the egg carton from a sheet of suitable material using conventional molding techniques.

The invention in its broader aspects is not limited to the specific details shown and described and departures may be made from such details without departing from the principles of the invention and without sacrificing its chief advantages.

We claim:

1. A packaging carton comprising a bottom section having a front wall and a rear wall; a cover section having a front wall and a rear wall, the cover and bottom sections' rear walls being hingedly connected so that the cover section can assume

a closed superimposed position with respect to the bottom section; and interlocking means on the front walls of the cover and bottom sections for releasably holding the carton closed, said interlocking means comprising:

- a. a locking flap hingedly connected to the bottom longitudinal edge of the cover section's front wall and foldable into overlapped relation with the inside of the cover's front wall;
- b. a plurality of spaced lockin detents projecting inwardly from the inside surface of the flap when it is in substantially folded overlapped position, said locking detents having an upper flat locking edge and depending sidewalls slanting toward the bottom of the locking flap;
- c. a plurality of spaced lugs projecting upwardly from the top of the front wall of the bottom section, each lug having a recess open at the front for receipt of a locking detent; and
- d. flat top walls on each of said lugs defining the top of said recess and forming a plurality of spaced locking lips corresponding to the plurality of locking detents; said locking lips engaging the upper flat locking edges of the locking detents as the sections are moved into closed position thereby pivoting the locking flap up into overlapped relation with the inside of the cover section's front wall and bringing the locking edges of the detents into locking engagement with the underside of the locking lips.

2. The carton of claim 1, in the form of an egg carton with the bottom section having a plurality of egg-accommodating cells.

3. The carton of claim 1, wherein the carton is of unitary molded construction.

4. The carton of claim 3, wherein the molded carton is formed of foamed polystyrene.

5. The carton of claim 1, including a locking flange, coextensive with the locking flap and extending beyond the locking edges of the locking detents, said locking flange abutting the forward edge of the locking lips when the sections are in closed position to hold the locking flap in locked position.

6. The carton of claim 5, wherein the hinged connection between the locking flap and the cover section's front wall resiliently urges the flap away from the inside of the cover's front wall so that the locking detents snap into their corresponding recesses in the lugs when the sections are moved into closed position.

7. The carton of claim 5, in which the hinged connection between the cover and bottom sections' rear wall resiliently urges the sections apart so that the locking detent's upper locking edges snap into tight engagement with the underside of the lugs' locking lips when the sections are moved into closed position.
